C. P. DUBBS

METHOD FOR TREATING PETROLEUM

Filed Dec. 29, 1919

Patented Feb. 3, 1925.

1,525,281

UNITED STATES PATENT OFFICE.

CARBON P. DUBBS, OF WILMETTE, ILLINOIS, ASSIGNOR TO UNIVERSAL OIL PRODUCTS COMPANY, A CORPORATION OF SOUTH DAKOTA.

METHOD FOR TREATING PETROLEUM.

Application filed December 29, 1919. Serial No. 347,973.

To all whom it may concern:

Be it known that I, CARBON P. DUBBS, a citizen of the United States, residing in Wilmette, county of Cook, and State of

Illinois, have invented certain new and useful Improvements in Methods for Treating Petroleum, of which the following is a specification.

This application is an improvement on my application filed June 21st, 1919, Number 305793, and for clarity, I herewith recite the description of the apparatus and describe the process as contained in my above mentioned application No. 305793, as

follows:

In the drawings:

Fig. 1 is a diagrammatic side elevation in section of an apparatus, by which my process can be carried out.

Fig. 2 is a top plan view of the vaporizing chambers and the immediate piping.

Fig. 3 is a top cross sectional view of that section of Fig. 1, in which the pools of oil are shown. This is a cross section taken on the line 3—3 of Fig. 1.

In describing the attached drawing, and operation of the process, the oil to be treated is drawn from a source (not shown), and is forced into the apparatus through valve marked K¹, through line K, through line K², which section is perforated that extends across the bottom of the top pool of oil in the chamber marked L^x. The portion vaporizing as said oil percolates up through this pool of oil is passed off through vapor line L, through the pressure regulating valve L¹, through gooseneck L², through condensing coil L⁴ positioned in condensing tank L⁷, through line L⁴ into tank M, along with the incondensable gases. Water is fed to tank L⁷ through line L⁵ and travels out of said tank through line L⁶. The condensate collected in tank M is drawn off through line M¹ having positioned thereon pressure regulating valve M², while the incondensable gas is drawn off through line M³ through pressure regulating valve M⁴ and on this tank is a liquid level gauge M⁶ and a pressure gauge M⁵. Tanks M and L⁷ rest on the supports marked x.

The level of the top pool of oil in the

chamber L^x is maintained at approximately the point marked J and any surplus flows through pipe J¹ into the pool of oil directly thereunder, the level of this pool being maintained at point marked J. Any excess travels through line J³ into the bottom of the pool of oil immediately thereunder, the level of each pool being maintained at point J and any excess travelling through the line J² into the pool of oil immediately thereunder and this pool is maintained at a level marked J and any excess travels through line J⁴, having positioned on it valve J⁵. At the bottom of line J⁴, the cross sectional area is reduced as shown at J⁶, the larger sized pipe used in J⁴ being for the purpose of allowing the oil to be, more or less, freed of any vapors contained therein, such vapors passing back up through said pipe into the bottom of the chamber L^x. The remaining liquid passes through line J⁶ to pump AA.

The heating tube B is disclosed as being of a continuous rebent formation, and is positioned within the furnace as clearly shown in Figure 1. The oil passes from the pump AA under pressure through this continuous coil where it receives its cracking heat, then passing through the transfer line C into one of the alternate chambers or tanks DD'.

The oil passes from the coil to the tank D which is of a large capacity, and wherein the oil undergoes conversion. The vapors generated from the oil pass through the vapor lines E into header E¹, through valve E² into line E⁴, which also has a pyrometer marked N. Through the line E⁴, the valve E⁶ being opened while the valves E⁷ and E¹⁰ are closed, the vapors pass into the bottom compartment of the chamber L^x. Any proportion condensing drains into the bottom compartment of chamber L^x, and is automatically returned to the heating tubes B through line J⁴. The uncondensed portion passes up through the pipes marked F¹ and by means of caps G is forced down and discharged near the bottom into the pool of oil in that chamber. The bottoms of the caps marked G are perforated at the points marked H. The vapors as they

bubble up this pool of oil give up more or less of their heat and more or less of same are condensed and as they bubble up through this liquid, they are more or less scrubbed. The excess oil accumulated in this pool travels through pipe J^2 into the pool of oil contained in the compartment directly thereunder, the pipe J^2 extending down into the pool of oil to a point near the bottom, thus forming a liquid seal so that no vapors contained in the lower chamber can pass up through pipe J^2 into the upper chamber. The remaining vapors pass up through pipes F^2 and are forced by means of caps G^1 down to near the bottom of the pool of oil contained in this chamber and there escape into said pool of oil through the perforations at a point marked H in said caps or if these are not of sufficient capacity, the excess vapors can pass clear down under the bottom of the caps and escape up through the oil from that point.

As such vapors percolate up through this pool of oil, more or less of the heat in same is extracted and acquired by the pool of oil, thus causing more or less of the vapors to condense and be retained in such pool of oil and act to have a scrubbing effect on remaining vapors. The surplus oil accumulating in this chamber travels through pipe J^3 into the pool contained in the chamber immediately thereunder, such pipe extending to near the bottom of said latter pool, so as to prevent any vapors passing therethrough from the latter chamber up into the former chamber. The remaining vapors in the last mentioned pool pass up through pipes F , and by means of caps G^2 are forced down to near the bottom of the pool of oil contained in this chamber and are there discharged into said pool of oil through the perforated places marked H or by passing completely under the bottom of caps G^2 and as they percolate up through this pool of oil, more or less heat is extracted therefrom and retained in the oil forming this pool, which causes more or less of such vapors to be condensed and retained in this pool of oil and the surplus of such oil overflows through pipe J^1 into the pool immediately thereunder, being discharged in said pool near the bottom so as to prevent any vapors in said lower chamber passing through this pipe into the upper chamber. There may be as many pools of oil as are shown in the chamber L^x or as desired or found necessary to sufficiently scrub the vapors passed there-through and to reduce and condense any desired portions of the vapors to produce the desired boiling point, the remaining vapors passing from said chamber L^x through pressure, regulating valve L^1 , through goose-neck L^2 as already de-

scribed. These pools of oil may be contained in one chamber as shown in the drawing and marked L^x or in more than one chamber. The excess oil in the bottom pool of each chamber being returned to the heating pipes B in the same manner as shown in the drawing, and as this will be readily understood by those versed in the art, I have not deemed it necessary to show more than one chamber marked L^x . 75

In case it is desired to stimulate the flow of vapors from the vaporizing chamber into and through the chamber L^x , a pump is provided marked E^8 and connected to the vapor line E^4 by means of line E^6 , having positioned on it valve E^7 and on the discharge side of the pump it is connected to vapor line E^4 by line E^9 , having positioned on it valve E^{10} and to use this pump for pumping, the valve E^5 would be closed 80 on line E^4 and valves E^7 and E^{10} would be open, and pump put in operation, thereby causing the vapors to travel from line E^4 through line E^6 , through pump E^8 , through E^9 , back through line E^4 on the opposite 90 side of the valve E^5 from which the vapors were originally drawn from line E^4 .

In different parts of this vaporizing chamber are shown pyrometers marked N and pressure gauges marked P . The chamber L^x and pump E^8 are positioned on supports marked x . The portion of oil in the vaporizing chamber D remaining unvaporized is drawn off either continuously or intermittently through line D^2 through valve D^5 and with it is carried off more or less of the carbon formed in the cracking of the oil. Vaporizing chamber D is duplicated as shown in vaporizing chamber marked D^1 . This is for the reason that when it 100 becomes necessary to clean vapor chamber D , the rest of the apparatus can be kept in operation by diverting the flow of heated oil coming from the heating tubes B into the other vaporizing chamber D^1 by the opening of valve C^3 and the vapors passed therefrom by the opening of valve E^3 , and the unvaporized portion in tank D^1 being drawn off through valve D^6 through line D^4 and the discharge of the heated oil into 110 tank D being stopped by the closing of valves C^2 and E^2 . In due time, the manholes marked D — D on this latter tank can be opened and the tank cleaned; said tank will be ready to be put back in service by 120 the time it becomes necessary to clean tank D^1 , this being done by the closing of valves C^3 , and E^3 and the opening of valves C^2 and E^2 . These vapor chambers are supported by supports marked X . Said vaporizing chambers and vapor line marked E and section of vapor line marked E^1 are heavily insulated as indicated by D^3 . The purpose 125 of such insulation is for preventing loss of heat from this section and to prevent 130

any portion of the oil, after once being vaporized, from condensing and mixed back with that portion remaining in the vapor chamber unvaporized. These vapor chambers are maintained only partly full of oil.

It will be noted that the raw oil is fed into the top or last pool of oil, which is of the lowest temperature and flows from there into the next succeeding pool of oil, which is higher in temperature and then to the next, which is still higher, etc., thus being progressively subjected to increasing temperatures and also mixed with such oils as are condensed in these pools of oil and such mixture returned for further heating. Thus, the raw oil being fed in is being preheated before passing to the heating coils B and thus utilizing more or less of the heat given up by the vapors that are passed through these pools of oil. It will be noted that by this novel arrangement, such portions of the oil, either of the raw oil fed in or that formed by condensing of portions of the vapors as they pass through the different pools of oil, that are changed to the desired low boiling point products, pass through the water condenser, and are condensed and collected separately, thus avoiding the necessity of subjecting them to the heat of the furnace A⁶.

The annexed single drawing is a duplicate of the drawing in my pending application No. 305793, and the different parts are marked exactly the same, excepting the heating coil in annexed drawing is a one piece rebent continuous coil and hence the headers marked A in drawing of the previous application are not used in this application.

The improvements in this application over the previous one consist in having a pump marked AA and valve AA¹, said pump being used for forcing the oil from the bottom of the dephlegmator through the heating coils B at such speed as found most advantageous. The other improvement consists of placing coils marked BB in the dephlegmator marked L^x. These coils are so made as to pass a liquid through same and in this manner either absorb heat from the oil they are submerged in or contribute heat. In the former case the heat thus absorbed can be utilized for heating other oil such as pressure distillate produced by this process for the separation of the light end by evaporation and condensation.

I am claiming in a co-pending application the broad invention involved in forcing the reflux condensate free of residual oil under a mechanical pressure through the heating zone while the claims in this application are drawn to the invention herein disclosed in which the charging stock is first preheated in the reflux condenser by the heat extracted from vapors passing therethrough,

and this charging stock as well as the reflux condensate being then forced through the heating coil under a mechanical pressure.

It will be noted that by these improvements the velocity at which the oil is passed through the heating tubes is definitely controlled which is an important factor and of considerable value. Also that the temperature of the different pools of oil the vapors pass up through is definitely controlled which is very important and gives definite control over the separating of the products that are desired to be condensed and collected separately from those that are condensed in the different pools of oil and again subjected to a heat treatment. By this arrangement it will be seen that by these definite controls the process can be operated with the least variations which is an important factor.

The following illustrative run of the process may be given.

Gas oil from a Kansas field of, say, 32 Baumé gravity, is fed through the line K into the dephlegmator or heat interchanger, where it comes into physical contact with ascending vapors, and thence passes by the overflow pipes to the lower chambers into the line J⁴. It then goes into the closed coil B, thence to the vapor chamber D. The residue is drawn off therefrom while the vapors pass through the line E⁴ into the lower end of the dephlegmator. A pressure of 135 lbs. may be maintained on the entire system by suitably regulating the outlet valves and 50 per cent of the gas oil may be converted into pressure distillate of 50 Baumé gravity, containing 65 per cent of 58 Baumé gasoline. The temperature of the various pools of oil in the dephlegmator can be regulated by the coils BB, which may be filled with either a heating or a cooling medium; for example, the oil in the vapor chambers D and D' might be 800° F., the oil in the bottom pool 600° F., in the next pool 550° F., in the next pool 500° F., and in the top pool 400° F.

The quantity of oil supplied to the coil B from the line J⁴ is positively regulated by the speed and capacity of the pump AA.

I claim as my invention:

1. A process for treating hydrocarbon oil, consisting in passing a stream of oil in a single passage through a continuous cracking coil where said oil receives its cracking heat, in introducing the heated oil to an enlarged chamber where substantial vaporization occurs, in removing vapors from said chamber and introducing said vapors to a dephlegmator, in aiding in the condensation of the insufficiently cracked vapors passing through said dephlegmator by introducing to the dephlegmator charging stock which accumulates with the reflux condensate in

pools in the dephlegmator, in discharging unvaporized residue from said enlarged chamber without again admitting said residue to said cracking coil, in forcing 5 under an applied mechanical pressure intermingled reflux condensate and charging stock from the dephlegmator to the inlet side of said cracking coil for passage therethrough and maintaining the oil undergoing 10 conversion under a super-atmospheric pressure.

2. A continuous process of oil conversion, consisting in maintaining a treated body of oil heated at a cracking temperature in an 15 enlarged expansion chamber where vaporization of said oil occurs, in discharging said vapors to a dephlegmator for passage therethrough, in condensing the heavy insufficiently cracked vapors in said dephlegmator by introducing charging stock thereto, in discharging uncondensed vapors from the dephlegmator, and in heating said charging stock and condensate from the dephlegmator to a cracking 20 temperature for introduction to said expansion chamber by continuously forcing the same under mechanical pressure to the inlet side of a continuous elongated heating means to which heat is applied to pass therethrough 25 and to be discharged after said passage into said expansion chamber, in discharging residue from said expansion chamber without admitting the same to said elongated heating means, and in maintaining a super-atmospheric pressure on the oil undergoing 30 treatment in said system.

3. A continuous process of oil conversion comprising passing hydrocarbon oil in a stream through a continuous elongated passageway where said oil is subjected to a cracking temperature, in then passing the highly heated oil to an enlarged expansion chamber where a substantial portion thereof vaporizes, in discharging vapors from 40 said chamber to a dephlegmator, in substantially continuously introducing charging stock to the dephlegmator to condense the insufficiently cracked vapors and to heat said charging stock, and in continuously forcing intermingled condensate, free of carbon containing residual oil, and charging stock from said dephlegmator under mechanical pressure to the inlet side of said elongated passageway for passage therethrough for 45 treatment, in separately discharging residue from the expansion chamber without permitting said residue to enter said elongated cracking passageway, and in maintaining said system under a superatmospheric pressure.

4. A continuous process of converting heavy into lighter hydrocarbons, consisting in passing a stream of oil through a heating coil where said oil is subjected to a cracking 55 temperature, in passing the heated prod-

ucts to an enlarged chamber where vaporization of a substantial portion of the oil occurs, in discharging the vapors to a reflux condenser, in introducing charging stock to said condenser to commingle with the vapors 70 and assist in condensing the insufficiently cracked vapors, in forcing intermingled condensate and charging stock passing from said reflux condenser by a mechanical pressure to the inlet of said heating coil, in discharging heated liquid residue from said enlarged chamber without admitting the same to the heating coil, and in maintaining a super-atmospheric pressure on the oil undergoing 75 treatment.

5. A continuous process of converting heavy into lighter hydrocarbons, consisting in passing a stream of oil through a heating coil where said oil is heated to a cracking temperature, in discharging the heated hydrocarbon material from said coil to an enlarged chamber where vaporization of a substantial portion of the oil occurs, in discharging vapors from said enlarged chamber to a reflux condenser, in introducing charging stock to said reflux condenser to preheat said stock and to assist in condensing the insufficiently cracked vapors, in forcing said condensate and preheated charging stock under a mechanical pressure to the inlet of the heating coil, in discharging liquid residue from said enlarged chamber without admitting the same to the heating coil, and in maintaining the oil undergoing treatment 90 under a super-atmospheric pressure.

6. A continuous process of converting heavy into lighter hydrocarbons consisting in passing a stream of oil through a heating coil where said oil is heated to a cracking temperature, in passing the heated oil to an enlarged chamber where conversion occurs and from which chamber liquid oil is not permitted to return to the cracking coil, in discharging generated vapors to a reflux condenser, in introduction charging stock to said reflux condenser to assist in condensing the insufficiently cracked vapors, in collecting the condensate and heated charging stock in a body, in discharging the condensate and heated charging stock from said body, and in forcing the same under a mechanical pressure to the inlet side of said cracking coil, and in maintaining the oil undergoing conversion under a super-atmospheric pressure.

7. A continuous process of converting heavy into lighter hydrocarbons, consisting in passing a stream of hydrocarbon oil through a coil in a heating zone where said oil receives its cracking heat, in transferring the heated products to an enlarged chamber where conversion of the oil occurs, and from which chamber no liquid oil is permitted to return to the cracking coil, in passing generated vapors to a reflux condenser, in introducing charging stock to 125

said reflux condenser to condense the heavy insufficiently cracked vapors, in forcing reflux condensate, free of carbon containing residual oil, with the preheated charging stock from said reflux condenser under mechanical pressure to the inlet of said heating coil for passage therethrough, and in maintaining the oil undergoing conversion in said coil and in the enlarged zone under superatmospheric pressure.

8. A process of oil conversion, consisting in continuously advancing a stream of hydrocarbon oil through a continuous elongated coil disposed in a heating zone, where said oil receives its cracking heat, in delivering the heated oil to an enlarged zone where conversion of the oil occurs and from which zone the unvaporized oil is withdrawn and prevented from returning to the elongated coil, in introducing vapors generated from said oil to a reflux condenser, in substantially continuously admitting charging stock to said reflux condenser to preheat said stock and to condense the insufficiently cracked vapors, in forcing reflux condensate and charging stock discharging from said reflux condenser under a mechanical pressure continuously to the inlet of the cracking coil for passage therethrough, in discharging uncondensed vapors from the reflux condenser for final condensation and collection, and in maintaining a super-atmospheric pressure on the oil undergoing conversion, in the coil and enlarged chamber.

9. A process of oil conversion, consisting in continuously advancing a stream of hydrocarbon oil through a continuous elongated coil disposed in a heating zone, where said oil receives its cracking heat, in delivering the heated oil to an enlarged zone where conversion of the oil occurs, in introducing vapors generated from said oil to a reflux condenser, in substantially continuously admitting charging stock to said reflux condenser to preheat said stock and to condense the insufficiently cracked vapors, in forcing reflux condensate and charging stock discharging from said reflux condenser, under a mechanical pressure continuously to the inlet of the cracking coil for passage therethrough, in discharging uncondensed vapors from the reflux condenser for final condensation and collection, in withdrawing carbon-containing residue from said enlarged zone without again admitting the same to the cracking coil, and in maintaining a super-atmospheric pressure on the oil undergoing conversion in the coil and in the enlarged zone.

10. A continuous process for converting heavy into lighter hydrocarbons, consisting in passing hydrocarbon oil through a heating coil where said oil is heated to a cracking temperature, in transferring the oil to an enlarged receiver where conversion occurs, and

from which receiver no liquid oil is permitted to return to the heating coil, in maintaining a superatmospheric pressure on the oil passing through said coil, in passing generated vapors to a reflux condenser, in introducing charging stock to said reflux condenser to condense the heavy insufficiently cracked vapors, and in forcing reflux condensate, free of residual oil, with the preheated charging stock from said reflux condenser under a mechanical pressure to the inlet of said heating coil for passage therethrough.

11. A continuous process for converting heavy into lighter hydrocarbons, consisting in passing a stream of oil through a heating coil where said oil receives its cracking heat, in delivering the highly heated oil to an enlarged insulated expansion chamber where vaporization occurs, in discharging generated vapors to a reflux condenser, in introducing charging stock to said reflux condenser to accumulate in pools therein with which said vapors intermingle to condense the insufficiently cracked vapors, in discharging condensate and heated charging stock from said reflux condenser and forcing the same under a mechanical pressure to the inlet side of the cracking coil, in withdrawing unvaporized residue from said enlarged expansion chamber without again admitting said residue to the cracking coil, and in maintaining the oil undergoing treatment under a superatmospheric pressure.

12. A continuous process for converting heavy into lighter hydrocarbons, consisting in passing a stream of oil through a heating coil where said oil is heated to a cracking temperature, in passing the heated oil to an enlarged insulated expansion chamber located outside of the zone of heat where vaporization occurs, in discharging generated vapors to a reflux condenser, in introducing charging stock to said reflux condenser to accumulate with reflux condensate in pools therein and through which pools the vapors must pass to condense the insufficiently cracked vapors, in discharging the condensate and heated charging stock from said reflux condenser, and in forcing the same under a mechanical pressure to the inlet side of said heating coil, in continuously withdrawing unvaporized residue from said expansion chamber without again admitting the same to the cracking coil, and in maintaining the oil undergoing treatment under a superatmospheric pressure.

13. A continuous process of converting heavy into lighter hydrocarbons, consisting in passing a stream of hydrocarbon oil through a coil where said oil is heated to a cracking temperature, in passing the heated oil to an enlarged insulated expansion chamber where vaporization occurs, in discharging generated vapors to a reflux

condenser, in introducing charging stock to said reflux condenser in a single stream to pass therethrough and commingle with the vapors to condense the insufficiently cracked vapors, in forcing condensate and preheated charging stock under a mechanical pressure from the reflux condenser to the inlet side of

the cracking coil, in continuously discharging unvaporized oil from said enlarged insulated chamber without again admitting ¹⁰ the same to the cracking coil, and in maintaining a superatmospheric pressure on the oil undergoing treatment.

CARBON P. DUBBS.
